MACHINE FOR HANDLING SHEETS OF
MATERIAL, LABELS, AND THE LIKEPaul W. Fleischer, Weehawken, N. J., assignor to
New Jersey Machine Corporation, Hoboken,
N. J., a corporation of New Jersey

Application March 19, 1935, Serial No. 11,773

12 Claims. (Cl. 271—62)

The invention relates to machines for handling sheets of material such as paper sheets, labels and the like and more particularly to machines of the indicated type in which the sheets, labels or the like are individually removed in succession from a supply stack and conveyed to a feeding means for transfer to another point such as for instance, suitable mechanisms adapted to perform predetermined operations on said sheets, labels or the like. The invention contemplates particularly the improvement of the construction and operation of the means for separating and removing the sheets, labels or the like from the supply stack in individual succession, and the provision of a simple mechanism for efficiently performing such functions in operative association with an improved and efficient means for maintaining the upper end of the supply stack within certain predetermined levels relatively to said mechanism. Other more specific objects will appear from the description hereinafter and the features of novelty will be pointed out in the claims.

In the accompanying drawing, which illustrates an example of the machine without defining its limits, Fig. 1 is a fragmentary sectional elevation of a machine embodying the novel devices; Fig. 2 is a fragmentary plan view, partly in section, showing in detail certain features of said novel devices, and Fig. 3 is an enlarged detail section on the line 3—3 of Fig. 2.

The apparatus shown in Fig. 1 may be considered as part of a gumming machine for the purpose of exemplifying the type of machines for which the novel arrangements are particularly adapted, it being understood, however, that this illustrated example is not intended to define the limits of the instant invention.

With this in mind the machine illustrated in the drawing comprises a vertically movable table 10 adapted to support a supply stack 11 of sheets, labels or the like preferably arranged between upright guides 12, at least one of which may be adjustable toward and away from the other guide 12 to accommodate sheets, labels or the like of varying dimensions. The support or table 10 is carried by a vertically extending elevating bar 13 adapted to be automatically shifted upward at proper times in operative association with co-operating parts of the machine to maintain the upper end of the supply stack 11 within certain predetermined levels relatively to the sheet separating and removing means.

To exemplify this arrangement the elevating bar 13, in the illustrated example, is provided

with a vertical rack 14 arranged in mesh with a pinion 15 fixed upon a shaft 16 journaled for instance, in a housing 17 suitably mounted in the machine of which it forms a part. The shaft 16 further carries a one-way ratchet wheel 18 adapted to be rotatably actuated intermittently by means of a pawl 19, as will be more fully set forth hereinafter, any suitable means such as a conventional stop-pawl being provided, if necessary, to prevent unintentional return movement of said ratchet wheel 18; in the arrangement shown in Fig. 1, the pawl 19 is pivotally secured at 20 upon the one end of a rocking lever 21 loosely mounted upon the shaft 16. At its opposite end the lever 21 carries a projection 15 which is illustrated in the form of a plate 22 fixed in place in any convenient manner as clearly shown in Fig. 1; the purpose of the plate 22 or its equivalent and the operation of the mechanism so far described will be set forth more fully hereinafter. To insure a proper return of the lever 21 to its normal position, a spring 21^a may be provided for instance as illustrated in Fig. 1. For the purpose of establishing said normal position, the lever 21 may be provided with a depending lug 21^b which carries an adjustable projection in the form of a screw 21^c; the latter may be fixed in an adjusted position by a lock nut 21^d and is adapted to engage a fixed stop 17^a on the housing 17 to thereby arrest the pivotal movement of the lever 21 in one direction.

In the illustrated example, the transfer means for removing the upper terminal sheets, labels or the like from the supply stack 11, in individual succession, consists of a suction head 23 of suitable type connected, for instance, by means of a flexible tube 24 with a convenient source of suction; any conventional means may be provided for controlling the suction in the head 23 in proper operative timing with the associated elements of the machine. The suction head 23 as shown, may be carried by an arm 25 fixed upon a rock-shaft 26 arranged to be operatively rocked in proper timing for instance, by means of a lug 27 and link 28 operatively combined with a suitable cam or equivalent means in any conventional manner to effect the desired results.

In addition to being rocked the shaft 26 is adapted to be raised and lowered to properly manipulate the suction head 23 in the operation of removing successive sheets, labels or the like from the stack 11, and said shaft 26 accordingly is journaled in members 29 as illustrated in Fig. 1; while only one member 29 is shown in the drawing, it will be understood that at least two such

members in spaced opposed relation to each other and their co-operating actuating means are included in the machine. The members 29 in the illustrated example, are provided with forked 5 lower ends 30 which straddle a cam shaft 31 suitably journalled in the machine, and further carry rollers 32 which project into the cam grooves 33 of cams 34 fixed upon the cam shaft 31; the properly designed cam grooves 33 by acting on the 10 rollers 32 bring about the vertical movements of the members 29 and shaft 26 which are required in the operation of the suction head 23.

In the illustrated machine the sheets, labels or the like are carried from the stack 11 over an inclined feed plate 35 suitably supported in the machine, and delivered, by the suction head 23 to co-operating feed rolls 36 and 37 rotatably mounted in the machine in any conventional manner. For purposes of illustration, the feed rolls 36 and 20 37 are shown in proximity to a guide plate 38 whereby the sheets, labels or the like being fed by the feed rolls 36 and 37 are guided into surface engagement with a roll 39 located in approximately surface engagement with a co-operating 25 roll 40; the rolls 39 and 40 may, for instance, exemplify the gumming and adhesive transferring rolls respectively of a conventional gumming machine and may be journalled in the machine in any customary manner.

30 As the sheets, labels or the like are successively removed, by the suction head 23, from the stack 11, the height of the latter will gradually decrease and the level of the upper end thereof will become progressively lower; it accordingly becomes 35 necessary to periodically elevate the table 10 in order to maintain the upper terminal sheet, label or the like of the stack 11 in proper position for engagement and removal by the suction head 23.

In the illustrated example the means whereby 40 the periodic elevation of the table 10 is automatically controlled includes a control member 41 provided with a conduit for an air blast for the purpose to be more fully described hereinafter. The control member 41, in the illustrated example, is 45 constructed in the form of a nozzle or tube suitably shaped as shown in Fig. 1 and fixed upon a rock-shaft 42 illustrated in detail in Figs. 2 and 3; as shown in Fig. 1 the control member 41 is arranged to contact the terminal sheet, label or 50 the like of the stack 11 within the surface area thereof at a point adjacent to an edge of said terminal sheet, label or the like in the path of the upward movements of said stack 11. The rock-shaft 42 at one end is journalled in any 55 convenient manner in the machine and at its other end is rotatably mounted in a stationary bearing 43 provided with an aperture or air-inlet 44 adapted to register with a corresponding aperture 45 in the shaft 42; the latter is formed with 60 an internal axial chamber 46 with which the aperture 45 is in communication and which itself is in open communication with the index member 41. While the illustrated example shows only one control member 41, a plurality of such members may 65 be included in the machine, if necessary or desirable; in such case, all of said control members 41 will be mounted on the shaft 42 in open communication with the chamber 46 thereof. The aperture or air-inlet 44 of the bearing 43 is connected with a suitable source of air under pressure in any convenient manner, and accordingly, as shown, may be formed in a boss 47 constituting part of the bearing 43 and adapted to receive one 70 end of a tube 48 which leads to the aforesaid source 75 of air under pressure; the latter may comprise a

blower or air pump or any other customary device. With the arrangement set forth the control member 41, in addition to functioning as a device for controlling the automatic periodic elevation of the table 10 and stack 11 as will be explained 5 more fully hereinafter, constitutes means for discharging a stream of air to prevent the dragging of the terminal sheet, label or the like during its removal from the stack 11 and for assisting the removal of such terminal sheet, label or the like without disturbing the remaining uppermost sheets of said stack 11, as will also be more clearly set forth hereinafter.

The rocking of the shaft 42 in proper timed relation with the associated elements of the machine may be effected in any suitable manner, as for instance, by means of an arm 49 fixed on said shaft 42 and connected through the medium of a rod 50 or the like with one member of a bell-crank lever 51; the latter is suitably pivoted at 52 in 20 the machine and has its other arm provided with a roller 53 adapted to ride upon the periphery of the cam 34, a spring 54 being associated with said lever 51 for maintaining said roller 53 in contact with the periphery of said cam 34 if necessary. 25 As shown in Fig. 1, the cam 34 is formed with a throw section 55 adapted to swing the index member 41 away from the top of the stack 11 at the proper predetermined intervals; the major peripheral portion 56 of the cam 34 permits the control member 41 to rest upon the top sheet, label or the like of the stack 11 under normal conditions while the peripheral low section 57 of said cam 34 permits said control member 41 to swing downwardly when the top of the stack 11 drops below a predetermined level, to automatically bring about an elevation of the table 10 and the stack 11. To effect this result at the proper time and in the intended manner, the bell-crank lever 51 carries a pin 58 which projects into an elongated 40 slot 59 formed in a link 60 near the one end thereof, said pin 58 and slot 59 exemplifying a lost motion connection between the actuating means for operating the control member 41 and the means for periodically actuating the stack elevating mechanism, or specifically between the bell-crank lever 51 and the link 60; the opposite end of said link 60 is pivotally connected with an operating member 61 loosely mounted on the shaft 42 and forming an integral part of or being connected with a depending lever 62. At its lower end the latter is provided with a projection preferably in the form of an adjustable screw 63 and in any case located in registry with a bar 65 having its lower end cut away to provide a shoulder 66 as illustrated in Fig. 1. The bar 65 depends from and is pivotally connected at 67 with an arm 68 projecting from one of the members 29, said bar 65 by the action of the projection 63 being adapted to be swung from its normal position to 50 the left in Fig. 1 to bring the shoulder 66 into registry with the plate 22 or equivalent projection carried by the rocking lever 21 to thereby bring about an elevation of the table 10 and stack 11 in the manner to be more fully described hereinafter; the arm 68 is so dimensioned and the pivot 67 is so located that the bar 65, when free to do so, will automatically assume a depending position in which the shoulder 66 is out of registry with the plate 22 or its equivalent.

In the operation of the illustrated machine, the suction head 23 is actuated through the medium of the cam groove 33, rollers 32 and members 29, and by means of the lug 21, link 28 and associated mechanism, to successively pick up the uppermost 75

sheet, label or the like from the stack 11 and deliver it to the feed rolls 36 and 37 by which said sheet, label or the like is transferred to the gumming roll 39 or its equivalent dependent upon the type of machine in which the mechanism is incorporated; it will be understood that, in the aforesaid operation of the suction head 23, the suction therein is automatically controlled in such a manner that the uppermost sheet, label or the like will be picked up and released in proper operative co-ordination with the co-operating elements of the machine. During its transfer from the stack 11 to the feed rolls 36 and 37 by the suction head 23, the uppermost sheet, label or the like of the stack 11 assumes a position indicated approximately at *a* in Fig. 1 in which the control member or nozzle 41 is located below the said sheet, label or the like *a*. It will be understood that the air blast referred to hereinafter is not on or at the nozzle 41 while the roller 53 is on the portion 56 of the cam 34.

Because of the rotation of the cam 34 during these operations, the roller 53 passes from the portion 56 of the cam 34 to the throw section 55 thereof and the latter by acting upon the roller 53 and its associated elements will, at the predetermined moment in the operative sequence, rock the shaft 42 on its axis and thereby swing the control member or nozzle 41 in a direction away from the top of the supply stack 11, or upwardly and in an arc to the left in Fig. 1 from the position illustrated in Fig. 1 to a point outside of the surface area of the terminal sheet of the stack 11, that is to a position out of the path of movement of the uppermost sheet, label or the like as it is raised by the suction head 23. The aforesaid rotation of said shaft 42 will at the same time bring its aperture 45 into registry with the aperture or air-inlet 44 and thereby open the connection between the control member or nozzle 41 and the source of air under pressure with which the tube 48 is connected. As a result of this, a stream of air or air blast will issue from the control member 41 and be discharged beneath the sheet, label or the like *a* being removed from the stack 11; this stream of air will exert a lifting action on the aforesaid sheet, label or the like *a* sufficient to completely free the latter and prevent it from developing a drag upon the next succeeding sheet, label or the like of the stack 11. As soon as the throw section 55 of the cam 34 has passed by the roller 53, the latter will drop therefrom to thereby rotate the shaft 42 in a reverse direction to shift the aperture 45 out of registry with the aperture 44 and cut off the supply of pressure air to the control member or nozzle 41, and at the same time to swing the latter back into contact with the top of the stack 11.

During these operative steps the pin 58 of the bell-crank lever 51 will move in the slot 59 without actuating the link 60 in a manner to produce any operative effect, and the bar 65 will partake of the vertical movements of the member 29, the shoulder 66 being out of registry with the plate 22 or its equivalent and having no operative effect thereon. When, however, because of the successive removal of a sufficient number of sheets, labels or the like therefrom, the height of the stack 11 is recurrently reduced sufficiently to bring the top thereof below a predetermined level, the roller 53 will drop from the throw section 55 of the cam 34 into engagement with the low section 57 thereof, thereby causing the bell-crank lever 51 to develop an abnormal movement on its pivot 52. This abnormal pivotal movement will be sufficient

to cause the pin 58 of said bell-crank lever 51 to engage the lower end of the slot 59 and exert a downward pull upon the link 60 which will be transmitted to the operating member 61 and rock the same on the shaft 42 to thereby swing the depending lever 62 toward the left in Fig. 1; the projection or screw 63 of said lever 62 will accordingly engage the bar 65 and correspondingly swing the latter toward the left to bring its shoulder 66 into the path of the plate or its equivalent 22. As the member 29 now moves downwardly carrying the bar 65 with it, the shoulder 66 will press downwardly upon the plate 22 or its equivalent and thus will cause the lever 21 to be rocked on its pivot 16; this rocking of said lever 21 will cause the pawl 19 to rotate the ratchet wheel 18 and its associated pinion 15 in a direction to raise the rack 14 so that the elevating bar 13 and with it the table 10 and stack 11 will be correspondingly elevated. In this way the top of the stack 11 will automatically be again restored to a predetermined level for proper co-operation with the suction head 23 and other associated elements. As soon as this elevation has taken place or when the roller 53 passes from the low section 57 of the cam 34 to the major portion 56 thereof, the pin 58 by engagement with the upper end of the slot 59 will shift the link 60 upwardly and thus rock the operating member 61 and depending lever 62 in a direction to move the projection or screw 63 out of contact with the bar 65 back to the position shown in Fig. 1; the bar 65 being thus free to do so will automatically swing back to its normal position as soon as the member 29 again moves upwardly, and accordingly will shift the shoulder 66 out of registry with the plate 22 or its equivalent. At this stage the spring 21a will rock the lever 21 in a reverse direction back to the position shown in Fig. 1, the pawl 19 simply riding over the teeth of the ratchet wheel 18 in a return movement to a new position ready for the next operation for again raising the table 10 and stack 11.

The novel arrangement shown and described combines the control member and the means for preventing dragging of sheets from the stack by the application of a stream of air, in a single element and thereby materially simplifies the construction and operation with respect to existing mechanisms designed for similar purposes. The indicated arrangement furthermore is of maximum efficiency and reliability in operation and may be incorporated in any machine in which elements exemplified by sheets, labels or the like are to be individually removed in succession from a supply stack and delivered to associated elements or co-operating mechanisms.

Various changes in the specific forms shown and described may be made within the scope of the claims without departing from the spirit of the invention.

I claim:

1. In a machine including a support for a supply stack of sheets, labels or the like, transfer means for removing said sheets, labels or the like from said stack in individual succession, and elevating mechanism for raising said stack support, that improvement which comprises a stationary bearing having an air inlet in connection with a source of air under pressure, a rock-shaft journalled in said bearing and having an internal air chamber provided with an aperture normally out of registry with said air inlet, a control member on said rock-shaft arranged to engage the upper end of said supply stack and

constituting an air nozzle in open communication with the air chamber of said rock-shaft, actuating means operated in timed relationship with the transfer means for operating said rock-shaft
5 to swing said control member in a direction away from the top of said supply stack and to shift said aperture into registry with said air inlet whereby a stream of air is discharged through said control member beneath the sheet, label or
10 the like being removed from said supply stack, and means periodically operated by said actuating means at intervals predetermined by the recurrent reductions in the height of the supply stack to actuate said elevating mechanism whereby
15 the top of said supply stack is restored to operative relationship with said transfer means.

2. In a machine including a support for a supply stack of sheets, labels or the like, transfer means for removing said sheets, labels or the like from said stack in individual succession, and elevating mechanism for raising said stack support, that improvement which comprises a rock-shaft having an internal air chamber, a control member on said rock-shaft arranged to engage the upper end of said supply stack and constituting an air nozzle in communication with the air chamber of said rock-shaft, actuating means operated in timed relationship with the transfer means for operating said rock-shaft to swing said control member in a direction away from the top of said supply stack and for co-incidentally connecting the air chamber of the rock-shaft with a source of air under pressure whereby a stream of air is discharged through said control member beneath the sheet, label or the like being removed from said supply stack, and means periodically operated by said actuating means at intervals predetermined by the recurrent reductions in the height of said supply stack to actuate said elevating mechanism whereby the top of said supply stack is restored to operative relationship with said transfer means.

3. In a machine including a support for a supply stack of sheets, labels or the like, transfer means for removing said sheets, label or the like from said stack in individual succession, and elevating mechanism for raising said stack support, that improvement which comprises a movable control member arranged to engage the upper end of said supply stack and constituting an air nozzle, actuating means operated in timed relationship with the transfer means for moving said control member in a direction away from the top of said supply stack and for coincidentally connecting said control member with a source of air under pressure whereby a stream of air is discharged through said control member beneath the sheet, label or the like being removed from said supply stack, and means periodically operated by said actuating means at intervals predetermined by the recurrent reductions in the height of said supply stack to actuate said elevating mechanism whereby the top of the supply stack is restored to operative relationship with said transfer means.

4. In a machine including a support for a supply stack of sheets, labels or the like, transfer means for removing said sheets, labels or the like from said stack in individual succession, and elevating mechanism for raising said stack support, that improvement which comprises a stationary bearing having an air inlet in connection with a source of air under pressure, a rock-shaft journaled in said bearing and having an internal air chamber provided with an aperture normally out

of registry with said air inlet, a control member on said rock-shaft arranged to engage the upper end of said supply stack and constituting an air nozzle in open communication with the air chamber of said rock-shaft, actuating means operated in timed relationship with the transfer means for operating said rock-shaft to swing said control member in a direction away from the top of said supply stack and to shift said aperture into registry with said air inlet whereby a stream of air is discharged through said control member beneath the sheet, label or the like being removed from said supply stack, a movable bar operatively associated with said transfer means and located normally in inoperative relation to said elevating mechanism, an operating member loosely mounted on said rock-shaft, a depending lever movable with said operating member, a link connected at one end with said operating member and provided at its opposite end with an elongated slot, and a pin associated with said actuating means and extending into said slot, said pin, by periodic engagement with the lower end of said slot predetermined by the recurrent reductions in the height of said supply stack, pivotally actuating said operating member to cause said depending lever to shift said bar into operative relation to said elevating mechanism whereby the latter is operated to restore the top of said supply stack to operative relationship with said transfer means.

5. In a machine including a support for a supply stack of sheets, labels or the like, transfer means for removing said sheets, labels or the like from said stack in individual succession, and elevating mechanism for raising said stack support, that improvement which comprises a rock-shaft having an internal air chamber, a control member on said rock-shaft arranged to engage the upper end of said supply stack and constituting an air nozzle in communication with the air chamber of said rock-shaft, actuating means operated in timed relationship with the transfer means for operating said rock-shaft to swing said control member in a direction away from the top of said supply stack and for coincidentally connecting the air chamber of the rock-shaft with a source of an under pressure whereby a stream of air is discharged through said control member beneath the sheet, label or the like being removed from said supply stack, a movable bar operatively associated with said transfer means and located normally in inoperative relation to said elevating mechanism, an operating member loosely mounted on said rock-shaft, a lever movable with said operating member, a link connected at one end with operating member and provided at its other end with an elongated slot, and a pin associated with said actuating means and extending into said slot, said pin, by periodic engagement with the lower end of said slot predetermined by the recurrent reductions in the height of said supply stack, pivotally actuating said operating member to cause said depending lever to shift said bar into operative relation to said elevating mechanism whereby the latter is operated to restore the top of said supply stack to operative relation with said transfer means.

6. In a machine including a support for a supply stack of sheets, labels or the like, transfer means for removing said sheets, labels or the like from said stack in individual succession, and elevating mechanism for raising said stack support, that improvement which comprises a movable control member arranged to engage the upper end of said supply stack and constituting an air nozzle, actu-

- ating means operated in timed relationship with the transfer means for moving said control member in a direction away from the top of said supply stack and for coincidentally connecting said 5 control member with a source of air under pressure whereby a blast of air is discharged through said control member beneath the sheet, label or the like being removed from said supply stack, normally inactive means controlling the operation 10 of said elevating mechanism, and a link connected with said normally inactive means and having a lost motion connection with said actuating means whereby said normally inactive means is periodically actuated at intervals predetermined 15 by the recurrent reductions in the height of said supply stack to operate said elevating mechanism and restore the top of the supply stack to operative relationship with said transfer means.
7. In a machine including a support for a supply stack of sheets, labels or the like, transfer means for removing said sheets, labels or the like from said stack in individual succession, and elevating mechanism for raising said stack support, that improvement which comprises 20 a combined control and air discharge means, a compressed air supply conduit, mechanism for operating said combined control and air discharge means in timed relationship with said transfer means to periodically connect said combined control and air discharge means with said compressed air supply conduit to thereby discharge a blast of air beneath the sheet, label or the like being removed from said supply stack, and means periodically operated by said mechanism at intervals 25 predetermined by the recurrent reductions in the height of the supply stack to actuate said elevating mechanism and restore the top of said supply stack to operative relationship with said transfer means.
- 40 8. In a machine including a support for a supply stack of sheets, labels or the like, transfer means for removing said sheets, labels or the like from said stack in individual succession, and elevating mechanism for raising said stack support, that improvement which comprises a combined control and air discharge means, a compressed air supply conduit, and co-operating means for operating said combined control and air discharge means to periodically connect said combined control and air discharge means with said compressed air supply conduit to thereby discharge a blast of air beneath the sheet, label or the like being removed from the supply stack and for actuating the elevating mechanism at intervals predetermined by recurrent reductions in the height of said supply stack to restore the top of the latter to operative relationship with said transfer means.
- 45 9. In a mechanism for periodically elevating a progressively decreasing stack of sheets, labels or the like, the combination of a compressed air supply conduit, an elevating control member co-operating with said progressively decreasing stack to maintain the upper end thereof at a predetermined level and provided with a conduit for 50 an air blast adapted to facilitate removal of terminal sheets, labels or the like from said stack, and a valve controlling said compressed air supply conduit and operated by said elevating control member to periodically connect its conduit with said compressed air supply conduit.
- 10 10. In a mechanism for elevating a progressively decreasing stack of sheets, labels or the like, an elevating control member co-operating with said progressively decreasing stack to maintain the upper end thereof at a predetermined level and provided with a conduit for an air blast, means for operating said control member, and means operated by said control member for controlling an air blast through said conduit in timed relation to the movements of said control member to prevent a terminal sheet being removed from the stack from developing drag on the next succeeding sheet thereof.
- 15 11. In a mechanism for elevating a vertical stack of sheets, labels or the like to compensate for reductions in the height of said stack because of the removal of upper terminal sheets therefrom, the combination of means operative at the forward edge of a terminal sheet of said stack for removing said terminal sheet therefrom, a control member adapted to contact the upper terminal sheet, label or the like within the surface area thereof at a point adjacent to said forward edge of said terminal sheet, label or the like in the path of upward movement of said stack, said control member in co-operation with the progressively decreasing stack controlling the elevating mechanism to periodically restore the upper end of said stack to a predetermined level, and means for vertically moving said control member outside of the surface area of said terminal sheet, label or the like to prevent interference with the removal of upper terminal sheets, 20 labels or the like from said stack.
- 25 12. In a mechanism for elevating a vertical stack of sheets, labels or the like to compensate for reductions in the height of said stack because of the removal of upper terminal sheets therefrom, the combination of a control member adapted to contact the upper terminal sheet, label or the like within the surface area thereof at a point adjacent to an edge of said terminal sheet, label or the like in the path of upward movement of said stack, said control member in co-operation with the progressively decreasing stack controlling the elevating mechanism to periodically restore the upper end of said stack to a predetermined level and being provided with a conduit for 30 an air blast, and means for moving said control member outside of the surface area of said terminal sheet, label or the like to prevent interference with the removal of upper terminal sheets, labels or the like from said stack and coincidentally connecting the conduit of said control member with a source of air under pressure to project a blast of air beneath a terminal sheet, label or the like being removed from said stack to facilitate said removal.

PAUL W. FLEISCHER. 65
